ATTORNEY.

UNITED STATES PATENT OFFICE.

HENRY H. WAIT, OF ANDERSON, INDIANA.

TURBINE.

Application filed February 20, 1923. Serial No. 620,263.

It is the object of my invention to improve the construction of turbines. More specifically, it is the object of my invention to provide an efficient mounting of the stationary 5 blades in the diaphragms, whereby the blades are held firmly and properly in place at a minimum of cost and a maximum of rigidity in construction and efficiency in action; to provide non-expanding guide passages in appropriate diaphragms, by blades which not only permit economical construction but provide efficient stream-line passages and in addition are of unusually strong construction; and to provide a beam and cantilever dia- 10 phragm construction of great strength but light weight.

The accompanying drawing illustrates my invention:

Fig. 1 is a fragmentary elevation of a dia- 20 phragm through which there are non-expanding steam passages, showing the lower half of the diaphragm complete; Fig. 2 is a sectional development on the line 2—2 of Fig. 1; Fig. 3 is a section on the line 3—3 of Fig. 2; Fig. 25 4 is an enlarged radial section through an outer part of a rotating element and the adjacent diaphragms, to show the annular ribs.

The turbine comprises a casing 20 carrying 30 a plurality of diaphragms 21 which divide the turbine into a plurality of stages, for each of which there is a turbine wheel 23. The turbine wheels 23 are provided at or near their periphery with suitable blades 24 mounted in a suitable manner; but as the details of the moving blades and their mounting form no part of my present invention they are not illustrated in detail. One or more of the diaphragms 21 may have ex- 35 panding steam-passages, such as shown at the left of Fig. 4; while other diaphragms may have non-expanding steam-passages as indicated at the right of Fig. 4.

Steam is supplied to the high-pressure end 45 of the machine by any desired means, the steam passing successively through the turbine wheels and diaphragms in the usual manner.

The non-expanding passages such as are 50 present in the diaphragm illustrated at the right of Fig. 4 are provided by blades 45 which are mounted on the edges of the dia- phragm 21 between it and a clamping ring 46. The blades 45 are held in place between 55 the edge of the diaphragm and the clamping ring by radial members which extend inward

through the clamping ring, through the respective blades, and into the edge of the dia- phragm, as is clear from Fig. 1. Some of these radial members are screws 47; but there 60 may be less of these than the entire number of blades, and for the remaining blades the radial members are pins 48 driven in place. The pins 48 preferably have threaded holes 49 in their outer ends, to receive a suitable 65 screw for pulling the pin out when desired. In addition to these through members 47 and 48, each blade 45 also preferably has a dowel pin 50 between it and the edge of the dia- phragm, which dowel pin is eccentric with 70 respect to the through members 47 or 48, so that it co-operates therewith to prevent the blade from turning.

The blades 45 may or may not extend the full circumference of the diaphragm. On the dia- 75 phragm illustrated in Fig. 1, which is a diaphragm adapted for use near the high- pressure end of the turbine, the blading ex- tends only over part of the circumference, and for the remainder of the lower half of the dia- 80 phragm the annular blading space is sol- idly filled by an arc-shaped strip 51 which is clamped similarly to the blades 45 between the edge of the diaphragm and the clamping ring 46; and in that diaphragm the upper 85 half of the diaphragm may extend out radially as far as the outer edge of the clamping ring 46 provided on the lower half. In the dia- phragm or diaphragms near the low- 90 pressure end of the turbine, however, the blad- ing normally extends for the complete cir- 95 cumference, in which case both half dia- phragms are provided with clamping rings 46, and there is no strip 51. In this latter case, the diaphragm is completely carried by the rings 46; and the support given the dia- phragm from such rings through the blades 45, screws 47, and pins 48 is sufficient to with- stand the differential steam pressure between 100 the two sides of the diaphragm, without re- quiring any additional supporting posts for the diaphragm. By reason of this, the en- tire steam-passages between the blades may be utilized, and there will be no interruption 105 in the flow of steam around the circumfer- ence, thereby avoiding in the current of steam through the revolving blades these interruptions which would cause acceleration and de- 110 celeration losses at the blades where such in- truptions occur.

The blades 45, viewed radially, are thin at the edges and thick at the middle, with the

discharge edge extending further in the direction of rotation than the other. Each blade has two steam-engaging surfaces, each formed of elements parallel to the axis of that blade; and, viewed radially, the blade-face toward the direction in which the turbine wheels move is concave, while the other blade-face is convex at the middle part, with substantially straight flaring faces toward the edges. Viewing the clamping ring 46 and the edge of the diaphragm 21 in radial section, as in Fig. 3, the outer edge 55 of the diaphragm is substantially straight, paralleling the turbine axis, preferably with a slight 15 chamfer 56 on the high-pressure side, and a slight flare 57 on the low-pressure side; and, still viewing it in radial section, the clamping ring 46 on its inner or blade-engaging face 58 is of smaller diameter on the high-pressure side than on the low-pressure side, and is concavely curved outward from the small-diameter dimension on the high-pressure side almost to the larger diameter low-pressure side, though preferably for a small 25 distance inward from the low-pressure side it may have a straight portion 59. Those faces of the blades 45 and of the strip 51 which engage the edge of the diaphragm and the inner face of the clamping ring are properly shaped to fit such faces of the diaphragm and clamping ring; say that if desired the blade 45 or strip 51 need not follow the chamfer 56. Each steam passage 60 between adjacent blades 45 is bounded by the concave 30 face of one blade and the convex face of a neighboring blade, and by the outer edge face 55 of the diaphragm and the inner face 58 of the clamping ring. This steam passage 60, viewed tangentially as in Fig. 3, flares 35 from the high-pressure side to the low-pressure side; but viewed radially it converges from the high-pressure side to the low-pressure side throughout the length of the adjacent concave blade-face. This radially 40 viewed convergence is preferably slightly greater than the tangentially-viewed divergence, when it is desired to provide a drop in pressure of the steam passing through the diaphragm, as thereby the cross-section of 45 such steam passage is made slightly convergent as a whole, and thus forms a converging nozzle. Such a nozzle is preferably used in the last diaphragm. However, if substantially 50 no pressure-drop is desired in the passage of steam through a diaphragm, as is the case with the first diaphragm, the steam passage may be of substantially constant area throughout. This may be obtained by suitably arranging the angles and profiles; and 55 may be obtained to a certain extent with the same blades and the same clamping rings, by turning the blades slightly on their axes and shifting axially of the turbine the line of screws and pins 47-48 with relation to the 60 faces of the diaphragm, so that the discharge 65

edges of the blades are kept substantially at the discharge face of the diaphragm; in which latter case the receiving edges of the blades may be cut off to make them flush with their face of the diaphragm and of suitable 70 angle to receive the steam.

With this shape of passage, I am able to avoid in the steam passage any preliminary expansion and subsequent re-contraction, with its consequent losses, such as occur with 75 many types of blades. With my blades, any steam passage through the diaphragm does not contract at any point after having expanded.

In a diaphragm, such as that illustrated 80 at the left of Fig. 4, where expanding steam-passages are desired, these may be provided by blades 71 held in place on the periphery of the associated diaphragm by means of a clamping ring 68 similar to the ring 46 which 85 holds in place the blades 45 forming non-expanding steam passages.

Each diaphragm 21 must withstand a considerable differential pressure between its two sides, sometimes amounting to several 90 tons. To take care of this, with a reasonably light diaphragm structure, and to provide ample room for the rotating shaft at the center of the diaphragm, I use the structure shown in Fig. 1. The diaphragm as a whole 95 is a web; but built into this web and superposed upon each half of it are a plurality of intersecting ribs or beams 75, and cantilevers 76, the beams extending along chords of the circle of the diaphragm, and the cantilevers 100 extending inward from the circumference of the circle to meeting points with the beams. In the simple structure shown, the beams or ribs 75 extend across each half-diaphragm obliquely to each other to cross each other as 105 close to the shaft opening as possible, one end of each beam extending to the circumference as near as possible to the intersection of the circumference with the joint between the two halves of the diaphragms; and the cantilever 76 in each half-diaphragm extends inward from the circumference of the diaphragm at a point 90° from the joint, through the junction of the beams 75, to the shaft 110 opening. This network arrangement of 115 beams and cantilevers superposed on the web of the diaphragm makes a structure which is both strong and light.

The turbine wheels are also webs of strength, usually with a few holes there-through to equalize the pressure on the two sides of the web and prevent end thrust. The revolving blades project axially slightly beyond the ring of the wheel. On the wheel web near the edge thereof are one or more 120 annular ribs on each face, the ribs on the two faces preferably being opposite each other. As shown, there are two such annular ribs on each face of each turbine wheel, but this 125 number is variable either way as desired. 130

These concentric ribs 80 project axially a very slight distance further than do the blades 24, so that in case of any endwise movement of the rotating element it is these ribs 80 which strike the adjacent faces 81 of the diaphragms 21. This prevents the rotating blades from striking the stationary blades on any such endwise movement, and efficiently protects both sets of blades. Further, because the ribs 80 are comparatively narrow, there will be comparatively little injury from friction between them and the faces 81 of the diaphragms 21 if the ribs do rub on such faces.

In addition to this function of protecting the blades, the ribs 80 have additional functions. In the first place, they serve materially to stiffen the rotating wheel-web. In the second place, they serve as baffles to break up the currents in the surrounding medium caused by the rotation of the wheel; as in any such rotating wheel the steam in engagement with the surface of the rotating member is entrained and thrown outward, and this involves an inflow along the surface of the adjacent diaphragms. These rotational losses due to this circulating fluid-flow increase approximately as the fifth power of the diameter. By providing the ribs 80, this flow is broken up, into a much smaller central section and one or more comparatively small outer annular sections, the number depending on the number of ribs 80, on each side of the rotating wheel web; and this results in a material reduction in the rotational losses from this cause.

I claim as my invention:

1. In a turbine, the combination of a casing, a diaphragm dividing said casing into stages for separate turbine wheels, a clamping ring 40 radially spaced from said diaphragm, a series of blades between said clamping ring and the edge of the diaphragm and fitting against both, and means for clamping said clamping ring, blades, and diaphragm together, one of

the blade-abutting faces of said clamping ring 45 and diaphragm being concavely curved axially of the diaphragm.

2. In a turbine, the combination of a casing, a diaphragm dividing said casing into stages for separate turbine wheels, a clamping ring 50 radially spaced from said diaphragm, a series of blades between said clamping ring and the edge of the diaphragm and fitting against both, and means for clamping said clamping ring, blades, and diaphragm together, 55 the blade-abutting faces of said diaphragm and clamping ring being relatively flaring toward the low-pressure side of the diaphragm, and one of said faces being concavely curved axially of the diaphragm. 60

3. In a turbine, the combination of a casing, a diaphragm dividing said casing into stages for separate turbine wheels, a clamping ring 65 radially spaced from said diaphragm, a series of blades between said clamping ring and the edge of the diaphragm and fitting against both, and means for clamping said clamping ring, blades, and diaphragm together, the inner face of said clamping ring fitting upon said blades and being axially 70 concave.

4. In a turbine, the combination of a casing, a diaphragm dividing said casing into stages for separate turbine wheels, a clamping ring 75 radially spaced from said diaphragm, a series of blades between said clamping ring and the edge of the diaphragm and fitting against both, and means for clamping said clamping ring, blades, and diaphragm together, the inner face of said clamping ring 80 fitting upon said blades and being axially concave and of larger diameter on the low-pressure side than on the high-pressure side.

In witness whereof, I have hereunto set my hand at Indianapolis, Indiana, this 19th day of February, A. D. one thousand nine hundred and twenty-three.

HENRY H. WAIT.
